VENDING MACHINE

Alfred E. Reimers, Harrington Park, and Walter K. Tavender, Haworth, N. J., assignors, by mesne assignments, to Automatic Equipment, Inc., New York, N. Y., a corporation of Delaware

Application June 28, 1933, Serial No. 678,000

2 Claims. (Cl. 312—68)

This invention relates to vending machines and our improvements, which pertain to the class of vending machines comprised in our earlier applications, Serial No. 589,822, filed January 30, 1932, and Serial No. 609,300, filed May 4, 1932, are directed to certain modified forms of some of the mechanisms employed in performing the functions of the machine, said modifications constituting further developments in the art.

For instance, our present improvements include modified means, actuatable in the operation of the pull-rod, to elevate the article rise-limiting finger into spaced relation with the topmost article of the stack, after said finger has lifted the brake-bar to cause the brake to be applied.

Another feature comprised in the application is that of novel means for raising the lodged coin, which cause it, in the first part of the movement of the pull-rod, to release the lock catch holding the kick-off mechanism from delivering an article, and permitting delivery to be effected.

A still further feature consists of novel coin lodgement means that support only a proper coin of the exact designated diameter, and reject all smaller coins or tokens.

Also our improvements include the provision of hinged gates that, when open, facilitate the replenishment of the magazine.

Also, our improvements include the provision of guards, adjustable as to height, carried by the hinged gates, for preventing withdrawal of articles below the topmost.

Still further our improvements include the feature of automatic opening and closing means for the coin slot, operable by the brake-bar in its up and down movements, the upward movement of the brake-bar causing the closure means to open the slot, and the downward movement of the brake-bar causing the closure means to close the slot.

Also in our improvements the table which supports the stack of articles is adjustable in its area between the stack guides, so that it may carry stacks of articles of varying sizes.

Other features and advantages of our invention will hereinafter appear.

In the drawings:

Fig. 1 is a side sectional elevation of our improved vending machine, taken on the line 1—1 of Fig. 2.

Fig. 2 is a front sectional elevation of the machine.

Fig. 3 is a partial side sectional view, taken on the line 3—3 of Fig. 4, showing the kick-off mechanism before operation.

Fig. 4 is a front sectional view, taken on the line 4—4 of Fig. 3.

Fig. 5 is a similar view to Fig. 3, showing the kick-off mechanism in operation.

Fig. 6 is a horizontal section, taken on the line 6—6 of Fig. 1.

Fig. 7 is a detail, being a horizontal section of the washer catcher, taken on the line 7—7 of Fig. 3.

Fig. 8 is a similar view, taken on the line 8—8 of Fig. 3.

Fig. 9 is a perspective detail of the coin controlled release mechanism.

Fig. 10 is a top plan view.

Fig. 11 is a horizontal section taken on the line 11—11 of Fig. 2.

Fig. 12 is a horizontal section taken on the line 12—12 of Fig. 2.

Fig. 13 is a front elevation of one of the forward article guides, with the gate thereon closed.

Fig. 14 is a similar view, showing the gate open.

Fig. 15 is a partial, side sectional elevation, taken on the line 15—15 of Fig. 13, and

Fig. 16 is a horizontal section taken on the line 16—16 of Fig. 13.

In the figures, let 1 indicate the rear flange of the machine encasing frame, 2 the left side wall, 3 the base flange and 4 the front flange.

As in our application Serial No. 589,822, a vertically movable carriage 5 is employed, said carriage having a table 6 to support a stack of articles indicated at 7, and also having a governor to control its speed of travel, said governor being generally indicated at 8 and corresponding with the governor mechanism disclosed in our said application, Serial No. 589,822. Weights, here shown at 9, are connected by a cable 10 with the carriage, said cable passing over a pulley 11, enabling the weights to serve as means for urging the carriage upwardly. Fixed upper and lower members 12, 13 support the four vertical rods 14, that form a rectangular guide for the weights 9, which latter are notched as at 15 to receive said rods.

The carriage 5, which is to be moved upwardly by the weights, is guided by a rack bar 16, having a rack 17, which is engaged by a pinion (not herein shown), forming part of the gear train included in the governor mechanism, all of which is merely referred to herein, it being fully described and illustrated in our said earlier application, Serial No. 589,822.

Cable 10, which has a tubular housing 10a, is shown as provided with a terminal block 18, that engages under a weight supporting table 19, and

the other end of the cable is shown connected with the table 6, as at 20, a spring 21 serving to cushion this connection.

Also the weights are adapted to be supported, in 5 a raised position, while the carriage is being re-loaded, by means of a chain 22, that is passed over a pulley 23 and lies within a recess 24 formed in the sides of the weights, said chain having a terminal member 35, attached to a block 36, said 10 chain passing through a slot in table 19 and said block, when drawn upwardly, engaging the table 19 and causing the weights 9 to be hoisted away from the terminal member 18. Then the chain may be caught upon the fixed tooth 37 which projects from the upper, forward frame portion 38, to thus hold the weights in their hoisted position during the carriage reloading process.

The brake-bar 39, connected by pivotal links 40 at the upper and lower frame portions, is attached at its upper end to a horizontal channel member 41, that carries a bent finger 42, whose lower, horizontal, terminal portion 43 lies normally upon the topmost article of the stack 1, in order that, as the stack rises after the delivery 25 of the topmost article, the succeeding topmost article will be moved into contact with portion 43 in the rising action of the carriage, causing finger 42 to raise member 41 and brake-bar 39, thereby causing the brake to be applied to stay the upward travel of the carriage, through the mechanisms which are fully shown and described in our said earlier application, Serial No. 589,822.

A traveller 44, in the form of a pair of spaced parallel plates, connected together, and having 35 intermediate rollers, 45, is mounted by said rollers upon a fixed, horizontal bar 46, and is adapted to be moved to and fro by means of a pull-rod 47 that is provided with a forwardly projecting handle 48. Said pull-rod is pivotally connected at 49, 40 to a lever, that is fulcrumed at its upper end to the wall 2, as at 51, and is pivotally connected, at its lower end, to a pendent portion 52 of traveller 44, as at 53, by which means a relatively short pull upon the pull-rod imparts an adequate travel 45 movement to the traveller.

Also said traveller 44 carries the kick-off means, here shown as comprising a pair of horizontal, spaced members 54, which are adapted to lie across the top of the topmost article, said members 54 having depending spurs 55, that hang behind the topmost article, to eject it in the forward movement of the pull-rod. Also the members 54 have forward, pendent lips 56, that hang in front of the topmost and next succeeding articles, to prevent delivery in short, to and fro shifts of the traveller before the lock release mechanism, which will be described hereinafter, has been actuated.

Means for locking the traveller 44 against forward movement are provided as follows: A pawl or latch 57, pivoted as at 58 to wall 2, lies in the path of a block 60 or stop which projects from the traveller 44, it being necessary to elevate said pawl so that it will clear block 60 to permit the operation of the pull-rod for delivery of a topmost article. Also the pawl 57 carries a tooth 59 to co-act with block 60 as a secondary stop. For the purpose of so elevating the pawl 57 we employ an interponent, which may be in the form of a proper coin 61, that has been introduced through a coin chute 62, and deposited upon an inclined shelf 63 that is fixed to the wall 2, said coin lying with its sides between the wall of said traveller and the spring finger 75 64 that is extended from traveller 44 and has an

angled terminal portion 65, the diameter of said coin being gauged so that it will become peripherally lodged between the angled portion 65 and the inclined shelf 63. Whereas if a smaller coin were introduced through the coin chute, it would not become so lodged but would roll down the shelf 63 and be ejected from the machine, instead of falling into the coin box 66.

With a proper coin ledged in the manner described the outward movement of traveller 44, effected by drawing upon pull-rod 47, causes said coin to travel up incline 63 on the horizontal surface 67, that forms a continuation of shelf 63, the coin, in its upward travel having peripheral contact with the under surface of a flange 68 that projects from the side of pawl 57, thereby lifting said pawl to clear it from opposition to member 60, thus permitting the traveller to be pulled out to the full extent of the pull-rod stroke, in which operation the spurs 55 will perform their function of delivering the topmost article. During this outward travel the coin will fall from surface 67 on to the inclined surface 69, whence it will be deposited into the coin box 66. If pull upon the pull-rod ceases short of delivering an article, and the coin has been carried past angle 51a, to rest on 69, then the angle 57a blocks the coin and prevents return of the traveller until completion of the stroke and delivery of the article. In this way the passing of the coin into the coin box, without delivery of the article, is avoided.

Pivotedly mounted in a bracket 70 that extends from the brake-bar 39 is a roller 71 that, in the normal position of traveller 44 (see Fig. 3), lies opposed to an incline 72 formed in a clearance 13 that is provided in the upper portion of the traveller. As said traveller is moved outwardly for an article delivery operation, incline 72 contacts with roller 71 and raises said roller on to the horizontal well 74, thereby also raising brake-bar 39 and with it the finger 42, to create a clearance between terminal portion 43 and the topmost article which is to be delivered.

The additional elevation thus imparted to the brake-bar beyond that given it in the rise of the carriage, occurs during the first part of the pull-rod movement, whilst the spurs 55 are moving up to the topmost article, so that there may be no frictional contact between the terminal portion 43 and the topmost article, that might otherwise tend to mar such article in its delivery movement.

Also, the traveller 44, which is returnable as by means of a weight 75, pendent by a cable 76, that passes over a sheave 77 and is connected with said traveller as at 78, returns the kick-off device to the position in which the spurs 55 are behind the vertical plane bounding the rear of the stack of articles, see Fig. 5, before permitting the rollers 71 to descend the incline 72.

The roller 71 remains on dwell surface 74 to hold brake-bar 39 up until the traveller 44 has returned to normal, taking the block 60 back behind pawl 57, thus preventing the stack from rising to present the next article to the delivery point before the traveller is locked.

The stack supporting table 6 has a pendent flange 79 that is provided with a horizontal slot 80, a thumb screw 81 penetrating said slot and engaging the carriage, to bind the table in an adjusted position. Upon loosening the thumb screw the table may be shifted to adjust its width so that the table may accommodate stacked articles of variable width. This table adjust-

ment is necessary because vertical guide members are employed that confine the stack laterally, one of these guides being fixed and the other adjustable. Thus, at 82 appears an upper 5 transverse member, which is braced as at 83 to the frame portion 38, and also secured to wall 2, and at 84 appears a lower transverse member which is secured, as at 85', to the wall 2. A fixed 10 vertical guide member 86 is secured to both these members 82, 84, to confine the stack laterally at the left side thereof. Also each of the members 82, 84 have a horizontal slot 85, to receive thumb screws 186 that respectively gauge a vertical guide member 87 that confines the stack at its right 15 side. The thumb screws 186 are adjustable in slots 85 to permit lateral shifting of the member 87.

A bracket 88, secured as at 89 to the wall 2, is disposed rearwardly of and in a lower plane 20 than member 84, said bracket 88 having a slot 90 for the lateral adjustment of a thumb screw 91, that is carried by a flange 92 of the guide member 87.

Also, to confine the stack rearwardly we provide 25 vertical guide members 93, 94, the guide 93 being adjustably connected, top and bottom with fixed brackets 95 by screws 96, that ride in slots 93a, and the guide 94 having adjustable connection top and bottom, with the guide 87 by screws 30 97 that engage slots 98 in said guide 87.

By the adjustable guide means thus described 35 the stack of articles, of different lengths and widths, may be confined both laterally and fore and aft, and held in alignment. The forward flanges 99 of guides 86, 87 maintain the front alignment of the stack, up to a certain height. Hinged to the guides 86, 87, above flanges 99, and 40 constituting continuations thereof are a pair of gates 100 having locking hinges 101, said gates, when closed and locked covering the front of the right and left end portions of the articles, to hold 45 them in alignment.

The gates, when lifted to relieve their hinge locks, may be swung open for the purpose of facilitating reloading the magazine.

Guards 102, having vertical slots 103, are adjustably connected to the gates 100 by means of 50 thumb screws 104, said guards, for convenience, having finger holds 105 whereby they may be shifted vertically, according to the thickness of the articles in the stack, to prevent removal of other than the topmost article.

The transverse member 41, which is connected 55 with the brake-bar 39, and moves therewith, carries a rod 105a that is connected therewith as by a member 106, said rod 105a engaging a coin slot closing plate 107 that is pivoted, as at 108, the upward movement of the brake-bar causing plate 107 to swing to the slot open position, and the 60 downward movement of the brake-bar causing plate 107 to swing to the slot closing position. Thus, whilst vendible articles remain on the carriage the coin slot will be uncovered because of the upward urging of said carriage by the weights 65 and the recurringly presented contact of the topmost stack article with finger portion 43. But, if no article remains on the carriage table, the brake-bar will fail to be actuated and hence the coin slot will remain closed.

The cable 10, carrying weights, is of such adjusted length that the weights will come to rest 70 upon their base support when the carriage has

reached its topmost position with no article thereon to engage the finger portion 43, so that the table 6 will be thereby halted in spaced relation with said portion 43, and thus the table, devoid of articles, will fail to actuate the brake-bar, in consequence whereof the coin slot will remain closed. 5

A magnet 109 is shown as positioned in the path of coin travel, to intercept magnetizable disks and prevent them from becoming lodged in 10 the manner of a true coin for operation of the machine.

Also, as means for intercepting non-magnetizable washers we employ a dog 110, pivoted at 111 to a bracket 112 that is secured to wall 2, said dog 15 having a tooth 113 and being urged by a spring 114 to impale a washer that may have become lodged upon shelf 63. Spring 64 has a slot 115 formed therein, and another spring 116, that lies against spring 64, has a clearance 117 that exposes slot 115. It is by means of clearance 117 and slot 115 that tooth 113 may engage the washer as the traveller is moved outwardly, leaving the washer impaled behind, and thus incapable of lifting the pawl 57, which is the function 25 of a true coin. What happens is that the washer becomes caught between the wall of the traveller and the two points of springs 64 and 116, because spring 116 also has an angled terminal portion 118, like the portion 65 of spring 64. Since the 30 forward movement of the traveller is checked by stop 60, it will be returned, and in this return movement the washer will be carried beyond the shelf 63 and ejected therefrom.

Variations within the spirit and scope of our 35 invention are equally comprehended by the foregoing disclosure.

We claim:—

1. The combination, in a vending machine, having a carriage adapted to support a stack of 40 articles, means for raising said carriage, braking means therefor, a shiftable brake-bar to operate said braking means, and means opposed to the topmost article adapted when contacted therewith to shift said brake-bar, of a slidable member 45 operable to deliver said article, and a roller carried by said brake-bar, said slidable member having an incline that co-acts with said roller in the initial part of the operation of said slidable member, to elevate said brake-bar and cause it to 50 release said opposed means from contact with said article prior to delivery of the latter.

2. The combination, in a vending machine, having a carriage adapted to support a stack of 55 articles, means for raising said carriage, braking means therefor, a shiftable brake-bar to operate said braking means, and means opposed to the topmost article adapted when contacted therewith to shift said brake-bar, of a slidable member 60 operable to deliver said article, said slidable member having a dwell surface and an incline leading upwardly thereto, a roller carried by said brake-bar and lying opposed to said incline in the normal position of said slidable member, said roller, in the initial part of the operation of said slidable 65 member being carried up said incline on to said dwell surface, thereby elevating said brake-bar and causing it to raise said opposed means out of contact with said article prior to delivery of the latter.

ALFRED E. REIMERS.
WALTER K. TAVENDER.
